UNITED STATES PATENT OFFICE.

CLAUD NORMAN JAY, OF MARLOW, OKLAHOMA.

AUTOMATIC RAILWAY-GATE.

1,244,336.

Specification of Letters Patent. Patented Oct. 23, 1917.

Application filed June 5, 1917. Serial No. 172,993.

To all whom it may concern:

Be it known that I, CLAUD NORMAN JAY, a citizen of the United States, and a resident of Marlow, in the county of Stephens and State of Oklahoma, have made certain new and useful Improvements in Automatic Railway-Gates, of which the following is a specification.

The invention provides a guard for rail-
ways to prevent persons and cattle from enter-
ing certain territory, so that trains and
cars may be operated without endangering
life and property.

The invention relates to a guard which is
normally projected across the track and
which is automatically withdrawn by the
train or car to admit of its unobstructed
passage, said guard automatically returning
to operative position when relieved of the
action of the train or car.

The invention consists of a novel form of
guard and actuating means which herein-
after will be more particularly set forth and
claimed, and which are shown in the draw-
ings hereto attached, which is an embodi-
ment thereof.

Referring to the drawings:—

Figure 1 is a top plan view of a section of
railway provided with a guard and operat-
ing means embodying the invention.

Fig. 2 is a section on the line 2—2 of
Fig. 1, looking in the direction of the
arrows, showing the parts on a larger scale,
and the foremost wheel of the truck about to
pass upon the depressible rail.

Fig. 3 is a transverse section on the line
3—3 of Fig. 1 showing the parts on a larger
scale.

Fig. 4 is a transverse section on the line
4—4 of Fig. 5, looking in the direction of
the arrows.

Fig. 5 is a plan view of the guard and
operating means showing the parts on a larger
scale.

Fig. 6 is a view similar to Fig. 4, showing
the relation of the parts when the guard is
depressed or withdrawn.

Fig. 7 is a detail perspective view of the
guard.

Fig. 8 is a sectional detail of a portion of
the guard showing the spring associated
therewith.

Fig. 9 is a transverse section on the line
9—9 of Fig. 4, looking to the right, as in-
dicated by the arrow.

Fig. 10 is a transverse section on the line

10—10 of Fig. 4, looking in the direction of
the arrow.

Fig. 11 is a detail perspective view of a
portion of a depressible rail showing the 60
parts intimately associated therewith.

Fig. 12 is a sectional view of a side por-
tion of the track on the line 12—12 of Fig. 1,
showing the parts on a larger scale.

Corresponding and like parts are referred 65
to in the following description and indicated
in the several views of the drawing by like
reference characters.

The numeral 1 designates the rails of a
track or line of railway provided with the 70
invention. The guard for safe-guarding
the track and preventing the entrance of
persons and cattle into prohibited territory
is disposed so as to extend between the rails
1 and for a short distance beyond the sides 75
of the track. In the drawings the guard is
illustrated as having a vertical movement
and when in operative position, is projected
vertically above the road bed, and when out
of the way, so as not to offer any obstruc- 80
tion to the passage of a train or car, the
guard is disposed or withdrawn below the
surface of the road bed, as indicated most
clearly in Fig. 6. The normal or projected
position of the guard is shown in Fig. 4. 85

The guard and actuating mechanism are
mounted in a casing 2, which is set in an ex-
cavation formed in the road bed. The case
2 is preferably closed at its bottom and
sides, and is open at the top to admit of ac- 90
cess thereto for any purpose. When the
parts are in place, a cap plate 3 closes the top
of the casing and is securely fastened there-
to. The casing 2 extends transversely be- 95
neath the rails, and to a suitable distance be-
yond the sides of the track so as to accom-
modate the guard and operating mechanism.

The guard comprises a beam 4 of a length
to extend across the track and beyond the
sides thereof a given distance. The ends of 100
the beam 4 are enlarged, as indicated at 5,
and are provided with standards 6, which
have a vertical disposition.

A plurality of fingers 7 project vertically
from the beam 4, and constitute guard ele- 105
ments. The fingers 7 and standard 6 are
adapted to operate through suitable open-
ings formed in the cap plate 3. Vertically
disposed guideways 8 are formed upon the
inner faces of the end walls of the casing 2, 110
and direct the guard in its vertical move-
ments. To reduce the friction between the

guard and casing to the smallest amount possible, rollers 9 and 10 are employed. The rollers 9 are mounted in depressions at the top of the end walls of the casing 2 in line with the guideways 8. The rollers 10 are mounted at the outer lower corners of the enlargements 5 of the beam 4.

The opposite end portions of the beam 4 are provided with longitudinal slots 11 to form a sliding connection with operating levers 12 of the operating mechanism. Members 13 are hingedly connected at their lower ends to the enlargements 5 of the beam 4, and are disposed so as to swing in the plane of the guard, and thereby admit of such guard covering a greater extent when projected than when withdrawn into the casing.

Springs 14 connect the members 13 with one another and with the standards 6. The springs 14 are flat, and are secured at their lower ends to certain members 13, and have sliding connection at their upper ends with the standard 6 and certain other members 13. When the guard is projected into operative position, Fig. 4, the members 13 are moved outwardly at their upper ends into fan shape by means of the springs 14. When the guard is withdrawn into inoperative position, Fig. 6, the upper ends of the members 13 are moved inwardly against the tension of the springs 14, and the outer faces of the outermost members 13 are flush with the extreme vertical edges of the enlargement 5, so as to engage the inner walls of the guideways 8.

The extreme members 13 travel upon the rollers 9 both when the guard is withdrawn into the casing or projected from the casing into operative position. The springs 14 yieldably connect the members 13 with the standards 6, and also limit the outward movements of the members when the guard is projected. The end portions of the springs 14 are formed with longitudinal slots 15, which receive suitable fastenings 16, Fig. 8. In this manner provision is had for movement of the springs as also to limit the outward movement of the members 13.

Depressible rails 17 are disposed adjacent the rails 1 and preferably upon the inner sides thereof, and may be of any length and mounted in any desired way. The rails 17 normally project a short distance above the treads of the rails 1 so as to be engaged by the wheels 18 of the trucks and be depressed thereby. As indicated in Fig. 3, the rails 17 are supported by means of expandible helical springs 19, mounted in casings 20 seated in the road bed, such casings being closed at their upper ends by means of caps 21.

A plunger 22 is seated upon each of the springs 19 and is mounted within the casing 20, and its stem 23 is connected with the

depressible rail. It is to be understood that any required number of spring supports such as indicated in Fig. 3, may be provided for each of the depressible rails. The depressible rails extend upon each side of the guard so as to be actuated by the approach of a train in either direction. The length of the depressible rails must be such as to insure complete withdrawal of the guard so as to avoid any injury thereto by the passing train or car.

A short length of rail 24 is provided at the outer end of each of the rails 17, and is pivotally connected to such depressible rails at 25, and to the rails 1 at 26. These short rails 24 constitute approaches to the depressible rails and are normally inclined to admit of the wheels 18 gradually riding upon and depressing the rails 17, Fig. 2.

Suitable operating means are provided between the depressible rails and guard to admit of the latter being withdrawn within the casing 2, when the rails 17 are depressed. This mechanism comprises the levers 12, which are pivotally connected at 27 to a bracket 28, projecting vertically from the bottom of the casing 2. The levers 12 are disposed upon opposite sides of the plane of the guard so as not to interfere with the vertical movements thereof, Fig. 10. The upper ends of the levers 12 are inwardly offset and are provided with pins 29, which enter the slots 11 of the beam 4, thereby providing pivotal and sliding connection between such levers and beam. The upper arms of the lever 12 are exceedingly long, whereas the lower arms are short, thereby providing for comparatively great length of movement of the guard as compared with the relatively slight movement of the depressible rails 17.

Links 30 pivotally connect the lower ends of the levers 12 to the inner ends of other levers 31, which are mounted upon standards 32 at 33. The levers 31 are disposed in a general horizontal position and operate vertically. Links 34 pivotally connect the outer ends of the levers 31 with L irons or brackets 35 connected to the depressible rail 17. The connection between the links 34 and irons 35 and between such irons and the depressible rails is adjustable, Fig. 11, to admit of adapting the parts as occasion may require.

The links 34, levers 31 and standards 32 are located at one side of the casing 2, and the upper ends of the links 34 are bent laterally so as to make connection with the irons 35, Figs. 9 and 10.

Rods or bars 36 are disposed near the ends of the casing 2, and are mounted in vertically disposed recesses 37 formed therein. Expansible helical springs 38 located in the recesses 37 support the rods 36 and admit of such rods having a downward movement.

when the rails 17 are depressed. The horizontal members of the L irons or brackets 35 resting upon the rods 36 are preferably secured thereto. The rods or members 36 in conjunction with the springs 38 yieldably support the rails 17 and may serve as stops to limit the upward movement of the guard when projected, Figs. 4 and 10.

To prevent shock when the guard reaches the limit of its upward movement, buffers 39 are located at the bottom of the casing 2, and these buffers engage opposite ends of the guard, Fig. 6. The buffers 39 preferably consist of springs of substantially V form, such springs being secured in any convenient manner to the bottom of the casing.

In the operation of the invention, the parts being assembled substantially as disclosed in the drawings and hereinbefore specified, the guard is normally projected by the combined action of the springs 38 and 19, since such springs serve to hold the rails 17 at the limit of their upward movement. When the guard is elevated the end portions comprising the members 13 are spread. When a train or car approaches the guard, the wheels 18 of the trucks engage the rails 17 and depress them, and this action moves the angle irons or brackets 35 and the rods 36 downward with the result that the outer ends of the levers 31 are depressed and their inner ends elevated, thereby operating the lever 12 and withdrawing the guard within the casing 2. As the guard descends into the casing the outermost members 13 are pressed inward and ride upon the rollers 9, the guard assuming the position when fully lowered into the casing, shown in Fig. 6. After the rails 17 are relieved of the weight of action of the train or car, the rails 17 are again elevated into normal position by the action of the springs 19 and 38, thereby resetting the mechanism and projecting the guard or gate into operative position, as indicated in Fig. 4.

It will be observed that the operation of the guard is automatic both when depressed and projected, the guard being lowered into the casing by the action of the train or car, and projected into operative position by the action of the springs in the manner stated.

Any moisture finding its way into the casing is adapted to escape through openings 40 formed in the bottom thereof; Fig. 6.

To prevent lateral displacement of the guard operating rails 17 from the track rails 1 clips 41 are employed. These clips are of U-shape and their vertical members extend along the outer sides of the rails. One member is preferably attached to the depressible rail; Fig. 12.

I claim:

1. Protective means for railways, the same comprising a guard mounted to have a vertical movement imparted thereto, oppositely

disposed levers arranged upon opposite sides of the guard, with their outer ends engaging opposite end portions of the guard, and actuating means coöperating with such levers and having connection at their inner ends therewith and adapted to be moved by a passing train or car to automatically withdraw the guard between the levers.

2. Protective means for railways, comprising a vertically movable guard, vertically disposed levers arranged upon opposite sides of the guard, with their upper-ends pivotally and slidingly engaging opposite end portions of the guard, horizontally arranged levers having connection at their inner ends with the lower ends of the vertically disposed levers, and means adapted to be actuated by the passing train or car and having connection with the outer ends of the horizontally arranged levers to effect depression of the guard.

3. Protective means for railways, the same comprising a vertically movable guard, vertically disposed levers arranged at the opposite sides of the guard and having their upper ends pivotally and slidingly engaging opposite end portions of the guard, horizontally arranged levers having linked connection at their inner ends with the lower ends of the vertically disposed levers, and train-operated means having linked connection with the outer ends of the horizontally arranged levers for depressing the guard.

4. In combination, a vertically movable guard, vertically disposed levers arranged upon opposite sides of the guard, with their upper ends pivotally and slidingly engaging opposite end portions of the guard, horizontally arranged levers, links connecting the inner ends of the horizontally arranged levers with the lower ends of the vertically disposed levers, train-operated members, and links connecting the train-operated members with the outer ends of the horizontally arranged levers.

5. In combination, a vertically movable guard, vertically disposed levers having engagement at their upper ends with the guard, horizontally arranged levers connected with the vertically disposed levers, train-operated members, yieldably supported members having directable movements and connected with the train-operated members, and links connecting the yieldably supported members with the said horizontally arranged levers.

6. In combination, a vertically movable guard, operating means for the guard including train actuated members, rods extending across the path of the guard to limit the upward movement thereof and having connection with the train operated members, and means for yieldably supporting the rods and normally holding the train operated members within the path of the train to be actuated thereby.

7. In combination, a vertically movable guard, operating means therefor including train actuated members, rods extending across the path of the guard to limit the upward movement thereof, means yieldably supporting the rods and normally holding the guard and the train operated members elevated, and means adjustably connecting such rods with the train operated members.
- 10 8. Protective means for railways comprising a casing, a guard movable vertically within the casing, vertically disposed levers mounted within the casing and having their upper ends pivotally and slidingly engaging

opposite end portions of the guard, horizontally arranged levers mounted within the lower portion of the casing, links connecting the inner ends of the horizontally arranged levers with the lower ends of the vertically disposed levers, depressible rails, links connecting the depressible rails with the outer ends of the horizontally arranged levers, rods extending across the path of the guard and yieldably supported at their ends within the casing, and connecting means between such rods and depressible rails.

CLAUD NORMAN JAY.
